UNITED STATES PATENT OFFICE.

PAUL ERNST PRESCHLIN, OF OBERUZWIL, SWITZERLAND.

PROCESS FOR APPLYING FIRMLY-ADHESIVE METAL CASINGS TO IRON CORES.

1,242,589.

Specification of Letters Patent.

Patented Oct. 9, 1917.

Application filed August 30, 1916. Serial No. 117,759.

To all whom it may concern:

Be it known that I, PAUL ERNST PRESCHLIN, engineer, a citizen of Switzerland, residing at Oberuzwil, Canton St. Gallon, and 5 Schladeron-on-the-Sieg, Switzerland, have invented certain new and useful Improvements in Processes for Applying Firmly-Adhesive Metal Casings to Iron Cores, of which the following is a specification, reference being had therein to the accompanying 10 drawing.

The invention relates to improvements in processes for the securing of metal casings on metal cores in the presence of heat.

In the now known processes of this character, it has been the practice to expand and contract a casing, under the influence of heat, onto a core for the securing of the same together, but, due to the fact that 15 the degree of contraction is not always equal to that of the expansion, the desired intimate contact or binding pressure does not obtain for the proper securing of the parts.

The primary object of the present invention is, therefore, to overcome this very objectionable feature heretofore obtaining in such processes, and to accomplish this result, it contemplates the providing of a means 20 for preventing any and all possible expansion of the casing, this means having a coefficient of expansion less than that of the casing, so as to exert a counter-pressure in opposition to that pressure produced by 25 the casing and core, and which consequently causes the contacting surfaces of the parts to firmly adhere one with the other when allowed to cool after heating.

The invention resides in the certain new 30 and useful process as will be hereinafter more fully described, set forth in the appended claims, and illustrated in the accompanying drawing, in which:

Figure 1 is a cross-section and fragmentary view of the preferred arrangement of the parts, when properly assembled for the carrying out of the process.

Fig. 2 is a view, similar to Fig. 1, of a modified arrangement, and,

Fig. 3 is another view, also similar to Fig. 1, showing a second modified arrangement thereof.

In the accompanying drawing, in which 55 similar characters of reference designate corresponding parts in the several views thereof, and in Fig. 1 thereof, the preferred

arrangement for the carrying out of the invention is shown, and the same comprises a core *a*, preferably cylindrical in form and made of iron or steel, which is adapted to 60 be inserted into a cylindrical casing *c* with a film of a suitable soldering metal *b* interposed between their opposed or contacting surfaces. In this instance, the casing is entirely inclosed within a coil of iron wire 65 *d*, preferably square or rectangular in cross-section, the convolutions of which are disposed in close contacting relation, as shown, and the coil is securely retained in this form by means of its opposite ends being 70 engaged in notches *g* formed in the ends of the core *c*.

Referring to Fig. 2, a modified form of the invention is shown, in which the core *a*, the film of solder *b*, and the casing *c* are assembled, as in Fig. 1, but the coil resistance *e*, performing similar function of that of the coil *d*, is wound over the surface of an auxiliary iron casing *h*, so that a concentric resistance is provided wherein its pressure 80 is distributed equally over the entire surface of the parts to be secured together. This auxiliary casing *h* may be slotted, as at *f*, or in any other suitable manner to facilitate its assembly or removal to and 85 from operative position.

In Fig. 3, there is shown another form of the arrangement of parts for the purpose of securing a casing on a core *a* of varying diameter, the same being assembled within 90 a casing *c*, with a film of the solder *b* interposed therebetween. The casing *c* is shaped to conform to that of the core *a*, or otherwise as may be desired, and is inclosed within an inner resistance casing *d*, which, in turn, is 95 inclosed within an outer resistance casing *k*. The outer resistance casing *k* is preferably of a form having a closed end and an open end, the latter being provided with a removable closure *l*, which is secured to the casing by means of bolts or screws *m*. The inner wall of the closed end of the casing *k* and the inner wall of the closure *l* are preferably 100 shaped to exert a clamping action on the several parts assembled therein, substantially 105 as shown.

In carrying out the process, in any instance, the metal core is coated with any suitable flux and soldering material and is inserted into its casing, after the contacting surfaces of both have been thoroughly cleaned and cleared from impurities and oxids, the 110

casing being drawn through a suitable gage-
plate so that it is firmly pressed upon the
core, and all air, contained between the core
and casing, is expelled. The resistance coil
or casing is now forced over the metal casing,
and the whole is then ready for the applica-
tion of heat thereto, for which purpose the
assembled body is placed into a suitable fur-
nace and heated up to a welding tempera-
ture. When heated to the desired tempera-
ture, it is taken from the furnace, and al-
lowed to cool, after which the resistance coil
or casing is then removed to complete the
operation.

This process may be carried out without
the application of the film of solder inter-
posed between the core and its casing, in
which case, the contacting surfaces, after
the heating operation, will be perfectly weld-
ed together, also the heating of the assem-
bled body may be effected by any suitable
form of electric heating apparatus in lieu
of the ordinary furnace.

It is to be fully understood that, while the
invention has been specifically described for
use in connection with cylindrical bodies,
cores and casings, various other forms of the
latter may be made use of without departing
from the spirit and scope of the invention.

What I claim as my invention and desire
to secure by United States Letters Patent
is:—

1. The process of securing metal casings
on metal cores, which consists in assembling
the core within the casing, heating the same
to a relatively high temperature, and sub-
jecting the casing to pressure to prevent its
expansion during the heating operation.

2. The process of securing metal casings
on metal cores, which consists in assembling
the core within the casing, heating the same
to a welding temperature, and subjecting the

casing to the action of a resistance for pre-
venting its expansion during the heating op-
eration.

3. The process of securing metal casings
on metal cores, which consists in cleaning
the contacting surfaces of the core and cas-
ing for freeing the same from all impurities
and oxids, assembling the core within the 50
casing, heating the same to a welding tem-
perature, and subjecting the casing to the
action of a resistance for preventing its ex-
pansion during the heating operation.

4. The process of securing metal casings
on metal cores, which consists in cleaning the
contacting surfaces of the core and casing
for freeing the same from all impurities and
oxids, assembling the core within the casing,
heating the same to a welding temperature, 60
subjecting the casing to the action of a re-
sistance for preventing its expansion during
the heating operation, and then removing the
resistance after the heat has been completely
dissipated.

5. The process of securing metal casings
on metal cores, which consists in cleaning the
contacting surfaces of the core and casing
for freeing the same from all impurities and
oxids, assembling the core within the casing,
interposing a film of soldering material be-
tween the apposed walls of the core and the
casing, heating the same to a welding tem-
perature, subjecting the casing to the action
of a resistance for preventing its expansion
during the heating operation, and then re-
moving the resistance after the heat has been
completely dissipated.

In testimony whereof I affix my signature
in the presence of two witnesses.

PAUL ERNST PRESCHLIN.
